DUSTLESS BAG EMPTYING ATTACHMENT

Edward G. Bender, New York, N. Y.

Application April 27, 1935, Serial No. 18,514

8 Claims. (Cl. 285—71)

The purpose of this invention is to provide a coupling or holder for bags and particularly dust collecting bags of vacuum sweepers by which a second bag may readily be attached to the dust collecting bag so that the dust may be dumped into the second bag without passing through the atmosphere.

The invention is a ring that may be inserted in an opening either at the upper end, side or lower part of a bag which is provided with circumferential clamping means by which the bag, and also the open end of a second bag, may be clamped around the ring providing a hermetically sealed connection between two bags so that the contents of one may be dumped into the other without escaping into the atmosphere. Bags of this type, and particularly vacuum cleaner bags, have been provided with closures at the upper ends which may readily be opened when it is desired to remove the dust from the bag; however, these closures only hold the end of the dust collecting bag and when another bag is slipped over the end thereof and dust dumped from one to another, there is an open space around the bag permitting the dust to escape therefrom, as there is no direct connection between the two bags. Other cleaners have been provided with vacuum bags of specially treated paper so that the air filters through the paper, leaving the dust in the bag and the entire bag is destroyed.

In both cases it is necessary to break the connection between the bag and the cleaner, which permits the escape of a certain amount of dust and it is, therefore, desirable to provide means for removing the dust or other contents from bags by forming a direct connection which positively connects one bag to another with a sealed joint.

The object of the invention is therefore to provide a coupling for clamping the ends of two bags together with one inside of the other.

Another object is to provide a coupling for connecting the ends of two bags in which the coupling may be inserted in a hem of one bag.

Another object is to provide an attachment by which the open ends of two bags may be positively connected which is detachable so that it may readily be removed when not in use.

A further object is to provide a coupling for clamping the open ends of two bags together in which the clamping parts clamp the ends of both bags with one over the other.

And a still further object is to provide a coupling for holding the ends of two bags together which provides a sealed connection which is of a simple and economical construction.

With these ends in view the invention embodies an open ring, a goose neck bracket attached to said ring and clamping members positioned around the outside of said ring and hinged to said bracket, said clamping members having clamps on the open ends thereof and said ring adapted to be opened with one end slideable in a socket in the end of the other.

Other features and advantages of the invention will appear from the following description taken in connection with the drawing, wherein:

Figure 1 is a view showing the attachment with the clamping rings partly open and with the dust bag indicated in dotted lines.

Figure 2 is a view showing a dust bag with the attachment incorporated in the open end thereof and showing the paper bag with the open end placed over the attachment as indicated in dotted lines.

Figure 3 is a cross section through the attachment with the goose neck shown in full lines.

Figure 4 is a plan view of the attachment with one side partly open.

Figure 5 is a view showing a dust bag with a paper bag held on the lower end thereof by the attachment and with a cleaning rod therein.

Figure 6 is a view showing an attachment of an alternate design in which it is formed with a tubular sleeve with clamping bands hinged to the outer surface thereof and with part broken away showing the clamping means on the opposite side thereof.

In the drawing the attachment is shown as it may be made wherein numeral 1 indicates the ring, numeral 2 the upper section of the goose neck, numeral 3 the lower section, numeral 4 one of the clamping members and numeral 5 a complimentary clamping member.

The ring 1 is preferably made of comparatively small round stock and it is preferred to make this ring with an opening therein in which a socket 6 is provided on one end into which the other end 7 may be inserted, as indicated by the dotted lines 8 shown in Figure 4. It will be understood, however, that an open ring of any type may be provided and any means may be used for holding the ends together. The upper section 2 of the goose neck extends upward from the socket 6, as shown at point 9 of Figure 3 and this part bends over so that the rod from which the goose neck is formed extends straight downward with a section 10 and then upward forming the section 3. The upper end of the part 3 is slightly smaller, forming a pin 11 extending upward from a shoul-

der 12 and the members 4 and 5 are hinged to the goose neck on the pin 11.

The members 4 and 5 are formed of crescent shaped material as shown at the point 13 in Figure 3 and these parts are connected to the parts 14 and 15 by which they are connected to the hinge 16 on the pin 11. The parts 14 and 15 are provided with open sockets 17 and 18 which fit around the section 10 of the goose neck as shown in Figure 4 providing clearance for the side of a bag placed therein. The parts 4 and 5 extend substantially around the ring 1 and the open ends are provided with clamping means as shown in Figures 3 and 4 in which the part 4 is provided 15 with a post 19 having a latch 20 pivotally mounted thereon and the part 5 is provided with a post 21 having a link 22 pivotally mounted thereon and it will be noted that a pin 23 shown in dotted lines in the outer end of the link 22 may be 20 gripped and held in a socket 24 in the member 20 so that when the latch 20 is forced downward against the member 4 it will draw the two members together and clamp the end of the bag or the ends of the bags around the member 1. It 25 will be noted that the upper end of the bag may be placed around a ring 1 with one side of the bag extending upward into the section 2 of the goose neck as indicated by the dotted lines 25, and then another bag may be placed over the 30 upper end of the former bag with the side thereof extending downward over the goose neck and into the socket in the section 3 thereof, as indicated by the dotted lines 26. The members 4 and 5 may then be brought together around the ends 35 of the bags and clamped together by the members 20 and 22. The upper end of the bag 25 may also be provided with a hem, as shown in Figure 1 and the open end 7 of the ring 1 may be inserted in a slit in the hem and the ring may be run 40 around so that it is installed in the hem forming the upper edge of the bag. The end 7 may then be placed in the socket 6 so that the device may be installed or mounted in the upper end of the bag and this may be covered with a piece of 45 cloth or a cap of any description that may readily be removed when it is desired to place a paper bag or other means for receiving the dust from the dust bag on the attachment.

The device may be installed in the upper end 50 of the bag as shown in Figure 2 in which the bag is indicated by the numeral 27 and it will also be understood that bags may be provided with these devices installed in both ends or in the upper end and also at a point 28 adjacent 55 the lower end so that a paper bag may be placed on the dust bag at the point 28 and the dust shaken into the bag without removing the bag 27 from a vacuum cleaner or the like. These devices may, therefore, be positioned at both ends 60 of the bag or at either end or at any point therein.

In the design shown in Figure 5 the bag 27 is shown removed from the sweeper and turned upside down with a paper bag 29 on the lower end thereof and this figure illustrates that the connecting ring 30 at the lower end of a dust bag may be covered by a cap 31 to close this end of the bag and the cap may be provided with a rod 32 which may be inserted into the bag for beating the interior thereof in order to free the dust from the walls. It may also be desirable to use a brush 33 on the end of the rod 32 so that the inner surface of the bag may be brushed. It will be understood, however, that any other 70 attachments may be used in combination with

this device for removing dust from dust bags or other objects or devices.

In the design shown in Figure 6 the device is formed with the tubular sleeve 34 having clamping rings 35 and 36 pivotally mounted on the 5 outer surface thereof with a hinge member 37 and the open ends of the bands 35 and 36 are provided with clamping means in which a latch 38 is pivotally attached to the end of one section of the ring by a hinge 39 and this latch is provided 10 with an opening 40 which fits over a leg or projection 41 on the end of the other section and by forcing the latch 38 over the projection 41 it is possible to draw the open ends of the bands 35 and 36 together to clamp objects on the surface to the member 34. 15

It will be understood that other changes may be made in the construction without departing from the spirit of the invention. One of which changes may be in the use of material of any 20 shape instead of the round stock shown in Figures 1 to 4; another may be in the use of other means for supporting the members instead of using the goose neck and another may be in the use of any other means for hinging the clamping 25 parts at one side of the ring.

The construction will be readily understood from the foregoing description. In use the device is provided, preferably, as shown in Figure 1 and the ring 1 may be placed inside of the upper 30 end of a bag or in the hem thereof and another bag placed over the ring and clamped thereto as hereinbefore described. The bag may then be inverted and as it is beaten or shaken, dust therefrom will pass into a secondary bag. This will 35 make it possible for any one using a vacuum cleaner to readily remove the dust from the dust bag by placing a common paper bag, in which groceries or the like have been carried home, with the open end over the ring and clamping it in 40 place. It also makes it possible for anyone to thoroughly clean a dust bag of a vacuum cleaner without permitting dust to escape to the atmosphere so that these bags may be cleaned in the 45 home without danger of the dust escaping. 45

It will also be understood that although this attachment has been shown and described as adapted for use with vacuum cleaners, it may also be used for any other purpose and with bags 50 of any other type or description. 50

Furthermore it will be understood that this device may be used on the opening in the lower end of the dust bag of a vacuum cleaner which connects to the discharge of the cleaner, and may be provided as a separate unit or combined with 55 the collar 30, shown on the lower end of the bag in Figure 2, in which case the opening in the upper end of the bag and also in the side may be omitted.

This device may also be used to hold a cover, 60 formed of a sheet of material, over the opening in the upper end of the bag, shown in Figure 2, or a cap, cover, or closure of any description may be used over the device to close the upper end of the bag. The paper bag or container, which is 65 indicated by the numeral 28, and which may also be made of any material may be folded downward into the end of the dust bag and this may form the closure or a cap or closure may be placed over the container and bag as may be 70 desired.

Having thus fully described the invention, what I claim as new, and desire to secure by Letters Patent, is:

1. An attachment for dust bags and the like, 75

comprising a ring adapted to be inserted in the open end of the bag with a holding member attached to one side, the holding member extending upward therefrom and then extending down-
5 ward beyond the ring, forming a socket, and then extending upward forming an oppositely positioned socket, and clamping means around said ring.

2. A device as described in claim 1 in which 10 the clamping means is hinged to the holding member.

3. A device as described in claim 1 in which 15 the clamping means comprises two semi-circular crescent shaped members, hingedly attached to the holding means and with clamping means on their open ends by which they may readily be clamped around the ring.

4. A device as described in claim 1 in which 20 the clamping means comprises two semi-circular crescent shaped members, hingedly attached to the holding means and with clamping means on their open ends by which they may readily be clamped around the ring, said ring having an opening therein and adapted to be inserted 25 in a hem in the end of a bag.

5. An attachment for holding the open ends of 30 two bags together, comprising a member adapted to be inserted in the ends of the bags clamping means adapted to hold the ends of the bags to the outer surface of said member, and means connecting the clamping means to the member

inserted in the ends of the bags, permitting the bags to be inserted over said member from the opposite sides thereof.

6. An attachment for holding the open ends of two bags together in sealed relation, comprising a circular member adapted to be inserted inside of the open ends of the bags clamping means adapted to hold the ends of the bags around said circular member, and means rigidly connecting the clamping means to the circular member, permitting the ends of the bags to be placed over said circular member from the opposite sides thereof. 5

7. A device as described in claim 6 characterized in that the clamping means comprises goose neck at one side of the ring with oppositely positioned sockets, permitting the sides of both bags to pass beyond the ring and having means rigidly mounting said clamping means over the bags held in the sockets of the goose neck. 10

8. An attachment for connecting the ends of bags, comprising a foundation member adapted to be inserted into the bags for holding the bags open, and with the ends of the bags continuously overlapping, means clamping the bags against 15 said foundation member, forming a substantially closed joint, and means rigidly connecting the clamping means to the foundation member, providing integral construction of the two parts. 20

EDWARD G. BENDER. 30
